N.B. Riddle INVENTOR.

BY

John Murphy Jr.

ATTORNEY.

UNITED STATES PATENT OFFICE.

NAPOLEON B. RIDDLE, OF ST. FRANCISVILLE, LOUISIANA.

SHOE-POLISHING APPARATUS.

Application filed August 5, 1920. Serial No. 401,408.

To all whom it may concern:

Be it known that I, NAPOLEON B. RIDDLE, a citizen of the United States, residing at St. Francisville, in the parish of West Feliciana and State of Louisiana, have invented certain new and useful Improvements in Shoe-Polishing Apparatus; and I do hereby declare the following to be a full, clear, and exact description of the invention, such as will enable others skilled in the art to which it appertains to make and use the same.

The object of the invention is to provide a simple, comparatively inexpensive and efficient portable shoe shining or polishing device suitable for example for domestic use or in connection with or as an adjunct of a shoe shining parlor, and with this object in view the invention consists in the construction and combination of parts of which a preferred embodiment is shown in the drawing, wherein:

Figure 1 is a side view of the apparatus.

Figure 2 is a longitudinal sectional view of the same.

Figure 3 is a longitudinal sectional view through the casing of the apparatus and its support.

The device consists essentially of a shank 10, preferably tapered in diameter and provided with a roughened or milled grip portion 11, to one end of which is attached a preferably spherical casing 12 of an electric motor, supplied by a flexible conductor 13, the shaft 14 of the motor extending axially through the shank 10 and being provided at its outer end with a socket 15. The brush or polishing head 16 which may be of any preferred construction, material, or form, is provided with a stem 17 fitted in the socket 15 and secured in place by means of a set screw 18 to the end that the polishing head may be changed or inter-changed with other heads, according to the work to be performed. The head may be secured to the stem by means of a retaining screw 19 or the equivalent thereof.

When the apparatus is not in use it may

be arranged with the spherical motor casing 12 in a suitable rest 20 concaved to receive the same, and the conductor 13 may be provided with a terminal plug 21 for attachment with a wall socket or equivalent of a house electrical service system. As shown in Figure 1, the rest 20 may be used to support the device while allowing freehand manipulation of the same about said rest as a pivoting point.

It will be obvious that an apparatus such as described may be conveniently located for domestic use and is adapted to serve its purpose with the minimum of effort and risk upon the part of the operator or may be used with advantage in those establishments wherein the public is served as a means of economizing time and effort upon the part of the operator and with better results than can be secured by the manual operation of polishing brushes or cloths.

Having thus described the invention, what I claim is:

1. A portable device of the class described having a casing comprising a handle, and formed at one end with an enlarged spherical portion, rotatable means in said handle, means in said portion and connected to said rotatable means to rotate the same, a supporting rest having a socket shaped to substantially correspond to and receive said enlarged portion to pivotally support said casing for hand manipulation.

2. A portable device of the class described having a substantially spherical casing, an elongated tubular handle extending therefrom, a motor within the casing having a driving shaft journaled in the handle and projecting beyond the free end thereof, and tool-securing means on said shaft beyond the free end of said handle.

In testimony whereof I affix my signature in presence of two witnesses.

NAPOLEON B. RIDDLE.

Witnesses:

ROBT TEMPFL,
D. D. BROOKS.
